UNITED STATES PATENT OFFICE.

WILLIAM A. BUTCHART, OF DENVER, COLORADO.

ТИЛТИНГ МЕХАНИЗМ ДЛЯ КОНЦЕНТРИРУЮЩИХСЯ СТОЛІВ.

1,345,662.

Specification of Letters Patent.

Patented July 6, 1920.

Application filed May 24, 1919. Serial No. 299,474.

To all whom it may concern:

Be it known that I, WILLIAM A. BUTCHART, a citizen of the United States, residing at Denver, in the county of Denver and State of Colorado, have invented certain new and useful Improvements in Tilting Mechanism for Concentrating - Tables, of which the following is a specification.

This invention relates to tilting mechanisms for concentrating tables and its primary object is to provide a device of this character which will change the transverse inclination of the table uniformly along its entire length and which includes a locking mechanism for securing its parts in their adjusted positions.

With this object in view, my improved mechanism provides a pivotal connection to one end of a pair of pivotally mounted beams upon which the table deck rests and extending transversely thereunder, so that by raising or lowering the pivoted ends the transverse inclination of the table deck can be varied to accelerate or retard the transverse flow of material under treatment.

The tilting mechanism consists of a pair of pinions mounted for rotation in unison in driving engagement with racks to which the beams are pivotally attached, and an appliance which by a simple adjustment locks the pinions against rotation and thereby secures the racks in their adjusted positions.

Having thus briefly explained the nature of my invention I will now proceed to describe the same in detail with reference to the accompanying drawings in the various views of which like characters of reference designate corresponding parts, and in which—

Figure 1 represents a plan view in outline of a concentrating table to which my invention is applied;

Fig. 2, an enlarged fragmentary elevation of the supporting and adjusting mechanisms;

Fig. 3, a further enlarged section taken on the line 3—3, Fig. 2;

Fig. 4, an enlarged transverse section on the line 4—4, Fig. 2, and

Fig. 5, a section taken on the line 5—5, Fig. 2.

Referring to the drawings, the reference character 2 designates the beams upon which the concentrating table deck 3 is supported and which extend transversely and parallelly beneath the same.

The beams are mounted by means of trunnions 4 to oscillate about a central transverse axis upon standards 5 and they are provided at their extremities with channelled 60 bearings 7 for the support of the concentrating table deck.

The table shown in outline in Fig. 1 is to this end equipped with four short rails 8 extending parallel to its longitudinal axis 65 adjacent its ends and resting loosely within the bearings 7 as shown in Fig. 4.

The adjusting mechanism which as hereinbefore explained is applied at one end of the parallel beams, consists of two standards 70 9 and 10 which have axially alined openings for the rotary support of a tubular shaft 12.

Pinions 13 secured upon the shaft by set-screws 14 have flanges 15 opposite correspondingly formed faces on the inner sides 75 of the standards, to provide guide-ways for rack-bars 16 which at their upper ends are pivotally attached to lugs 17 projecting from one of the ends of the two beams.

The rack teeth are formed along one of 80 the sides of longitudinal slots 18 in the bars, within which the pinions extend and the bars thus coöperate with the flanges on the pinion and the faces on the standards to constantly maintain the racks and pinions 85 in their coöperative positions.

A hand-wheel 19 mounted on the hollow shaft and preferably having handles 19^a at equal distances along its rim, provides a convenient means for the manual rotation 90 of the shaft.

The locking appliance of the mechanism consists of a rod 20 which extends loosely through the hollow shaft and projects beyond the ends thereof. A nut 21 on one of 95 the screw-threaded ends of the rod bears upon a cupped washer 22 which lies against the corresponding standard over the end of the hollow shaft, and another similarly recessed washer 23 which occupies a corresponding position upon the outside of the other standard, and has a spiral-cam-face which coöperates with a corresponding face on a cam 24 rotatably supported upon the end of the rod projecting through and beyond the washer.

A nut 25 screwed upon the end of the rod, holds the face of the cam in engagement with the cam face of the washer, and a dowel 26 on the standard 10 occupying a recess in the washer 23, holds the latter against rotation.

The cam 24 has a laterally extending handle 24^a to facilitate the rotary movement of its spiral-cam face upon the corresponding face of the washer 23.

- 5 It will be seen that when the cam is in its normal position in which its spiral-cam face lies loosely against that of the washer, the tubular shaft is free to rotate and that when its rotation is effected through the medium 10 of the hand-wheel 19, the co-operative engagement of the pinions with the racks on the bars 16 will cause the latter to move up or downwardly.
- 15 The movement of the rack bars compels the beams 2 to move about their pivotal axes with the result that the transverse inclination of the table deck supported upon the bearings at their extremities is changed accordingly.
- 20 To lock the parts in their adjusted positions the cam 24 is turned upon the washer 23 in the direction of the inclination of its spiral-cam face, thereby increasing the effective thickness of the washer lever face, and 25 forcing the standards 9 to spring slightly from their natural position and thus clampingly engage the rack-bars between the flanges 15 of the pinions 13 and corresponding flanges on standards 9 thereby preventing 30 rotation of the pinions and vertical movement of the rack bars.

It will be understood that my tilting mechanism may be attached to a concentrating table deck otherwise than by pivotal 35 connection to two supporting beams, without departing from the spirit of my invention.

Having thus described my invention what I claim and desire to secure by Letters-Pat- 40 ent is:

1. Adjusting mechanism of the character described, comprising in combination with a tiltably supported element, rack-bars pivotally attached thereto, bendable standards, 45 pinions rotatably supported thereon in operative engagement with racks on the bars, means to rotate the pinions, and locking mechanism acting upon the standards to cause them to frictionally oppose the co- 50 operative movements of the pinions and the racks.
2. Adjusting mechanism of the character described comprising in combination with a tiltably supported element, rack-bars pivotally attached thereto, standards, pinions rotatively supported thereon in operative 55

engagement with racks on the bars, means to rotate the pinions, and locking mechanism adapted to oppose rotation of the pinions by a clamping engagement between the standards and relatively movable parts.

3. Adjusting mechanism of the character described comprising in combination with a tiltably supported element, rack-bars pivotally attached thereto, bendable standards, 60 a shaft rotatably supported thereby, pinions on the shaft meshing with racks on the bars and having flanges co-operating with faces on the standards to form guide-ways for the bars, and locking means acting upon the standards to clamp the racks between their faces and the flanges of the respective pinions.

4. Adjusting mechanism of the character described comprising in combination with a tiltably supported element, rack-bars pivotally attached thereto, bendable standards, 65 a hollow shaft rotatably supported thereon, pinions on the shaft meshing with racks on the bars and having flanges co-operating with faces on the standards to form guide-ways for the bars, a rod extending through 70 the shaft and having a head, bearing on one of the standards, a cam-member fixed with relation to the other standard, and a rotary 75 cam-member on the rod, co-operating with the other member to bend the standards.

5. Adjusting mechanism of the character described comprising in combination with a tiltably supported element, rack-bars pivotally attached thereto, standards, a shaft 80 rotatably supported thereon, pinions on the shaft meshing with racks on the bars and mechanism adapted to oppose rotation of the shaft by a clamping engagement of the 85 standards and relatively movable parts.

6. Adjusting mechanism of the character described comprising in combination with a tiltably supported element, inclosed racks pivotally attached thereto, bendable standards, pinions rotatably mounted on the standards in operative engagement with the racks and having flanges opposed to faces on the standards to form guide ways for the racks, and mechanism acting upon the 100 standards to clamp the racks between their faces and the flanges of the respective pinions.

In testimony whereof I have affixed my signature.

WILLIAM A. BUTCHART.
